UNITED STATES PATENT OFFICE.

WILLIAM A. SCHLEICHER, OF CLEVELAND, OHIO, ASSIGNOR TO THE EBERHARD MANUFACTURING CO., OF CLEVELAND, OHIO, A CORPORATION OF OHIO.

DOOR FASTENER.

Application filed November 27, 1923. Serial No. 677,207.

To all whom it may concern:

Be it known that I, WILLIAM A. SCHLEICHER, a citizen of the United States, residing at Cleveland, county of Cuyahoga, and State of Ohio, have invented a new and useful Improvement in Door Fasteners, of which the following is a full, clear, and exact description.

The present invention relates broadly to door fasteners, and more particularly to door fasteners adapted to maintain in closed position a pair of doors which are disposed within the frame of a single doorway, such as the doors employed to close the rear end 15 of a covered delivery wagon.

An object of the invention is to provide a fastener for holding a pair of doors in closed position adapted to be moved to one position to release one of said doors while 20 maintaining the other of said doors closed and to be moved to another position to simultaneously release both of said doors.

A further object of the invention is to provide a fastener of the above type adapted 25 to prevent rattling or vibration of the doors when held in closed position thereby.

In the accompanying drawings, there is shown, for purposes of illustration only, one embodiment of the present invention, it 30 being understood that the drawings do not define the limits of the invention, as changes may be made in the construction and operation therein disclosed without departing from the spirit of the invention or scope of 35 my broader claims.

In the drawings:

Figure 1 is a view in elevation of a pair 40 of doors mounted in a door frame and equipped with a fastener embodying my invention;

Figure 2 is a view similar to Figure 1, but showing the fastener in position to release the right-hand door and showing the latter door in open position;

Figure 3 is a detail view on an enlarged 45 scale of portions of the fastener and fragmentary portions of the doors on which said portions are mounted;

Figure 4 is a sectional view on the line 50 IV-IV of Figure 3;

Figures 5, 6, and 7 are detail views of portions of the fastener; and

Figure 8 is a detail view illustrating the guide and keeper for one of the latch bolts.

Referring to the drawings, A and B designate 55 a pair of doors hinged at their outer vertical edges to a door frame C in which said doors are mounted. The right-hand door B is provided at its inner vertical edge on the outer face thereof with a metal strip D adapted to overlap the inner vertical edge of the door A when said doors are in the closed position thereof, shown in Figure 1.

My improved fastener comprises an operating 60 latch lever 2 which is hinged to a member 3 by means of a pivot pin 4. The member 3 is provided with an integral hollow stud 5 positioned in a bore 6 extending transversely through the left-hand door A adjacent the free inner vertical edge thereof and approximately midway between the upper and lower horizontal edges of said door. The door A has face plates 7 and 8 positioned on its outer and 65 inner faces, respectively, and secured to said door by means of bolts 9 extending through the door and the face plates. These plates overlie the bore 6 and have openings therein 70 in alignment with said bore. The stud 5 on the member 3 extends through the opening in the plate 7 and has a collar 10 swaged thereon on the inner side of said plate whereby the member 3 is journaled 75 in said plate, but is prevented from being separated therefrom.

A short lever 11 is positioned on the inner side of the door A and has an integral sleeve 12 extending through the opening in the plate 8 into the bore 6. This sleeve has a faceted end portion 13 of the hollow stud 5. A collar 14 is swaged on the sleeve 12 on the inner side of the plate 8, whereby the lever 11 is journaled 80 in said plate, but is prevented from being separated therefrom. A bolt 15 extends through the stud 5 and sleeve 12 and assists the bolts 9 in maintaining the plates 7 and 8 and the parts carried thereby in position 85 on the door.

The right-hand door B is provided with a keeper plate 16 on its outer face in alignment with the face plate 7 and secured to the door by screws 17. One end portion of the keeper plate overlies the door strip D, while the other end portion thereof is provided with an integral vertically extending keeper 18 offset from and parallel to the 90 100 105

outer face of the keeper plate. This keeper is provided at its upper end with an integral inwardly extending lip or shoulder 19.

The operating latch lever 2 is of channel shape in cross section, the channel of the lever facing inwardly towards the doors. This lever has a knob or handle 20 rotatably secured to its free end by means of a rivet 21. A plate spring 22 is positioned in the channel of the lever and is secured to said lever by the rivet 21 which extends through one end of the spring. This plate spring is bowed inwardly intermediate its ends, so that when the lever is engaged with the keeper 18, as shown in Figures 3 and 4, the bowed intermediate portion of the spring engages the end portion of the keeper plate 16 which overlies the door strip D. The positioning of the latch lever 2 behind the keeper 18 tends to straighten the spring 22 so that the latter exerts a constant pressure against the right-hand door B and serves to keep the doors tightly closed and to prevent any rattling of the same or of the parts of the fastener. The keeper plate 16 is provided at its lower edge with a depending outwardly offset lug 23 and the latch lever 2 is provided at its lower edge with a corresponding integral lug 24 positioned to overlie the lug 23 when the latch lever 2 is engaged with the keeper 18, as shown in Figure 3. Each of these lugs has an opening 25 therein to receive the hasp of a padlock, whereby the doors may be locked in closed position.

Positioned on the inner side of the door A is a pair of vertically extending latch bolts 26 and 27. These latch bolts have their adjacent ends flattened and pivotally connected to the opposite ends of the lever 11 by means of pivot bolts 28 carried by the lever and extending through openings 29 in said flattened ends of the latch bolts. These pivot bolts have anti-friction rollers 30 mounted thereon within the openings 29, said openings being of somewhat greater diameter than the external diameter of said rollers, whereby there is a slight amount of lost motion in the pivotal connections between the latch bolts and the lever. Mounted on the inner face of the door A adjacent the upper and lower horizontal edges thereof is a pair of guide brackets 31 through which the latch bolts 26 and 27 extend. Interposed between each bracket and the latch bolt cooperating therewith is a bowed leaf spring 32 adapted to prevent rattling of the bolt in its keeper. The free ends of the latch bolts engage keepers 33 on the inner face of the door frame C when the parts are in the position shown either in Figure 1 or in Figure 2.

Referring to Figure 6, it will be seen that the face plate 7 is provided with upper and lower lugs 34 and 35. These lugs form stop

shoulders for limiting the swinging movements of the member 3 which is journaled in the plate 7.

The operation of the fastener above described is as follows: When the parts are in position shown in full lines in Figure 1, both doors are held in closed position. With the parts in this position, if it is desired to open the right-hand door B while maintaining the left-hand door A closed, the operator will grasp the knob 20 and press the latch lever 2 inwardly to disengage it from the inwardly extending lip 19 on the keeper 18. He will then swing the latch lever vertically into the position shown in dotted lines in Figure 1, the said lever swinging about the pivotal axis of the member 3 to which it is hinged. When the latch lever has been moved into this position, it may then be swung outwardly away from the door B about its pivotal axis 4 into the position shown in Figure 2, and the door B may be swung to open position, as is also indicated in said figure. The movement of the parts into the position shown in Figure 2 will not serve to withdraw the latch bolts 26 and 27 from their keepers 33 by reason of the lost motion connections between said bolts and the lever 11. The position of the lever 11, and of the pivoted end portions of the latch bolts when the latch lever 2 has been moved into the position shown in dotted lines in Figure 1, is also shown in dotted lines in Figure 5, by reference to which it will be seen that the movement of the lever 11 into the angular position shown has taken up the lost motion in the pivotal connections between the latch bolts and the lever 11. Even if such lost motion connections were not provided, the movement of the latch lever 11 into the dotted line position shown in Figure 1 would not move the bolts sufficiently to withdraw them from their keepers because of the fact that the angular movement of the lever 11 from the position shown in Figure 1 to the position shown in Figure 2 would effect only a very slight longitudinal movement of the latch bolts. In order to release the door A, the latch lever 2 must be further swung about the pivotal axis of the member 3 sufficiently to withdraw the latch bolts 26 and 27 from the keepers 33. This will bring the member 3 against the stop 35 on the plate 7. When it is desired to again fasten the door A in closed position, the lever 2 will be swung about the pivotal axis of the member 3 until the parts are in the position shown in Figure 2. If now it is desired to fasten the door B in closed position, the latch lever 2 will be swung about its pivotal axis 4 until the lever is in position behind the lip 19 on the keeper 18 and then about the pivotal axis of the member 3 to engage said lever with said keeper.

The advantages of the present invention

arise from the provision of a fastener for a pair of hingedly mounted doors adapted to be moved into one position to release one of said doors while maintaining the other of said doors in closed position and then to be moved into another position to release said other door and also from the provision of a fastener of this character adapted to prevent all vibration or rattling of the doors.

10 I claim:

1. A door fastener, comprising a latch lever adapted to be secured to a door for pivotal movement with respect thereto about an axis located adjacent one end of the lever, keeper means for releasably securing the free end of said lever to a support, a handle mounted on the free end of said lever, a plate spring carried by said lever, said lever being of channel shape in cross section with the channel facing inwardly towards the door and said spring being positioned in said channel and having a bowed intermediate portion for engagement with said support when said lever is held by said keeper means, and common means engaging said handle and one end of said spring for securing said handle and spring to said lever, substantially as described.

2. The combination with a door frame and a pair of cooperating doors hingedly mounted therein, of a fastener for holding said doors in closed position, comprising latch means mounted upon one of said doors for holding said door in closed position and including a member mounted for pivotal movement about either of two axes, and a keeper mounted upon the other door for cooperation with said member for holding the latter door in closed position, said member being adapted to be first moved about one of said axes to release it from said keeper, then about the other of said axes to permit such last mentioned door to be swung to open position and then to be further moved about the first axis to release the first mentioned door, substantially as described.

3. The combination with a door frame and a pair of cooperating doors hingedly mounted therein, of a fastener for holding said doors in closed position, comprising a latch lever mounted upon one of said doors for swinging movement either about an axis at right angles to the plane of the door or outwardly from the door about an axis parallel to the plane thereof, a latch bolt operatively connected to said latch lever, for cooperation with said door frame for holding said door in closed position, and a keeper mounted upon the other of said doors and adapted to cooperate with said latch lever for holding the latter door in closed position, said latch lever being adapted to be swung about said first mentioned axis to release it from the keeper on the last mentioned door, then about the last mentioned

axis to permit the last mentioned door to be swung to open position, and then to be further swung about said first mentioned axis to release the first mentioned door, substantially as described.

4. The combination with a door frame and a pair of cooperating doors hingedly mounted therein, of a fastener for holding said doors in closed position, comprising a latch lever mounted upon one of said doors for swinging movement either about an axis at right angles to the plane of the door or outwardly from the door about an axis parallel thereto, a plurality of latch bolts carried by said door and operatively connected to said latch lever, keeper means on the door frame for cooperation with said latch bolts for holding said door in closed position, and a keeper mounted upon the other of said doors and adapted to cooperate with said latch lever for holding the latter door in closed position, said latch lever being adapted to be swung about the first mentioned axis to release it from the keeper on the last mentioned door, then about the last mentioned axis to permit the last mentioned door to be swung to open position, and then to be further swung about the first mentioned axis to withdraw said latch bolts from their keepers and thereby release the first mentioned door, substantially as described.

5. A fastener for a pair of swinging doors, comprising a member adapted to be journaled in one of said doors, a latch lever pivoted at one end to said member for swinging movement about an axis at right angles to the pivotal axis of said member, a pair of oppositely extending latch bolts operatively connected to said member and adapted to cooperate with a door frame for holding said door in closed position, and a keeper adapted to be secured to the other of said doors for cooperation with said latch lever to hold said last mentioned door in closed position, said latch lever being adapted to be swung about the pivotal axis of said member to release it from said keeper and permit it to be swung about its other pivotal axis to enable the last mentioned door to be swung to open position and then to be further swung about the pivotal axis of said member to release said latch bolts from the frame and permit the first mentioned door to be swung to open position, substantially as described.

6. The combination with a door frame and a pair of cooperating doors hingedly mounted therein, of a fastener for holding said doors in closed position, comprising a latch lever mounted upon one side of one of said doors for swinging movement either about an axis at right angles to the plane of the door or outwardly from the door about an axis parallel thereto, a latch bolt mounted upon the other side of said door for cooper-

tion with the door frame for holding said door in closed position and having a lost-motion operative connection with said lever, and a keeper mounted upon the other of said doors and adapted to cooperate with said latch lever for holding the latter door in closed position, said latch lever being adapted to be swung about the first mentioned axis to release it from the keeper on the last mentioned door, then about the last men-

tioned axis to permit the last mentioned door to be swung to open position, and then to be further swung about the first mentioned axis to operate the latch bolt and thereby release the first mentioned door, 15 substantially as described.

In testimony whereof I have hereunto set my hand.

WILLIAM A. SCHLEICHER.
